(57) **CLAIM**

The ornamental design for a round pressed tablet, as shown and described.

DESCRIPTION

FIG. 1 is a top perspective view of a round tablet showing our new design with portions shown in stippling to indicate color contrast;

FIG. 2 is a right end elevation thereof, the side opposite being a mirror image;

FIG. 3 is a front elevation, the side opposite being a mirror image thereof;

FIG. 4 is a top plan view thereof;

FIG. 5 is a bottom plan view thereof; and,

FIG. 6 is a top perspective view of a modified embodiment of the design shown in FIGS. 1 through 5, the other views being identical thereto apart from the lack of stippling to indicate color contrast.
